UNITED STATES PATENT OFFICE.

OSCAR GOERIZ, OF SAN FRANCISCO, CALIFORNIA.

CENTRIFUGAL PUMP.

No. 890,355.

Specification of Letters Patent.

Patented June 9, 1908.

Application filed January 8, 1907. Serial No. 351,297.

To all whom it may concern:

Be it known that I, OSCAR GOERIZ, a citizen of the Empire of Germany, residing in San Francisco, in the county of San Francisco and State of California, have invented 5 certain new and useful Improvements in Centrifugal Pumps, of which the following is a specification.

This invention relates to centrifugal 10 pumps, and more particularly to centrifugal pumps of the multistage type.

One object of the invention is to provide a 15 centrifugal pump with means whereby end-thrust in either direction may be entirely overcome.

A further object of the invention is to provide a centrifugal pump having improved 20 means whereby the water is received from the peripheral portion of each runner and conducted to the runner of the succeeding stage, said means effecting the transformation 25 of kinetic into potential energy and thereby increasing the pressure and the efficiency of the pump.

With these ends in view, the invention 30 consists in the novel features of construction and combinations of parts which will be hereinafter described and claimed.

In the accompanying drawings, in which 35 the same reference characters denote the same parts throughout the several views, Figure 1 is a vertical longitudinal section of a vertical three-stage pump constructed in accordance with the invention, Figs. 2, 3 and 4 are transverse sections on lines A, A, B, B, and C, C, respectively, Fig. 1, Fig. 5 is a vertical longitudinal section of a horizontal three-stage pump constructed in accordance with the invention, Fig. 6 is an enlarged detail section through the adjustable bushing-ring and its adjacent parts, Fig. 7 is a similar section showing a modified form of the bushing-ring, in which the flanges of the ring are independently adjustable, and Fig. 8 shows 45 another form of bushing-ring by which the hydraulic pressure from any stage in a multi-stage centrifugal pump may be controlled.

In the drawings 1 denotes, generally, the 50 casing of the improved pump which is divided, as usual, into an inlet-section, an outlet-section, and a number of intermediate sections.

2 denotes the inlet-section through which the fluid is sucked into the pump, and 3 the

outlet- or discharge-section, which is of the 55 usual form and provided with a discharge-pipe 4.

5 and 6 denote the sections of the casing in which the runners are rotatable, said sections being bolted to each other and to the 60 inlet and outlet sections, as shown.

The shaft 7 is journaled within the pump-casing in the usual manner and has arranged thereon three runners or impellers 8, 9, 10, the pumps illustrated being of the three-stage type. The fluid is received from the 65 runners 8, 9 by water-ways 34 which conduct the fluid to the inlet of the runner of the next stage.

The runners 8, 9, 10 are of the well-known 70 inclosed type having inclosed passages 11, as shown in Fig. 2. Each runner is provided with a suction-inlet 12 and with openings 13 by which communication is afforded with chambers 14 formed in the pump-casing at 75 the rear of each runner. The fluid in passing through the openings or ports 13 fills the chambers 14, and thereby creates in them a reduced pressure which counteracts, to a certain extent only, the end-thrust on the runners. The balancing-chambers 14 are shut off from the peripheral portions of the runners and casing-sections by coöperating 80 flanges 15, 16 extending respectively from the rear surfaces of the runners and the forward surfaces of the adjacent casing-sections. In this manner there is formed at the rear peripheral portion of each runner an annular chamber 17 which is in communication with the outlet of the adjacent runner. In advance of the runners 9 and 10 of the second and third stage, there are arranged in the 85 casing-sections 5, 6 annular chambers 18 which extend about the peripheral portions of said runners opposite the chambers 17. In advance of the runner 8 of the first stage there is an annular chamber 19 corresponding to the chambers 18, but of substantially greater capacity, said chamber being also of substantially greater capacity than the chambers 17. The chamber 19 in the vertical 90 pump, shown in Fig. 1, is formed in the inlet- or suction-section 2, while in the horizontal pump, shown in Fig. 5, it is formed partly in the inlet-section 2 and partly in a small section 20 interposed between the inlet-section 2 and the casing-section 5.

The chamber 19 communicates with the

suction-inlet of the inlet-section 2 through a space which is left between said inlet and the suction-inlet of the first runner 8, and said chamber also communicates with the outlet 5 of said runner by means of the space existing between the periphery of said runner and the wall of the casing-section. The chamber 19 is therefore in communication with both the suction-pressure and the discharge-pressure.

10 By this invention means are provided by which the communication between the chamber 19 and the suction and discharge pressures may be controlled at will, and thereby the amount of pressure on the runners in a 15 direction from the suction toward the discharge-end of the pump made such that the pressure in the chambers 14 and 17 at the rear of the runners is exactly counterbalanced and all end-thrust eliminated. Said 20 means comprise a bushing-ring 21 arranged within the chamber 19 and provided with flanges 22, 23 which control the communication between said chamber 19 and the suction and discharge pressures. The flanges 25 22 and 23 are concentric with each other and with the inner and outer walls of the chamber 19, upon which walls they are arranged to slide in a direction parallel to the pump-shaft, said flanges being connected by an annular web 24. Said bushing-ring is adjusted 30 by bolts 25 which extend into the casing and are threaded at their inner ends into the web 24. The connection between the casing-wall and said bolts is made water-tight by means 35 of a number of washers, as shown, and upon the outer ends of the bolts, which extend without the casing, are placed nuts 26 by means of which said bolts may be moved longitudinally, carrying with them the web 40 24 and flanges 22, 23 which form the bushing-ring. The nuts 26 are held against longitudinal movement by lugs 26^x formed on the pump-casing, and hence when they are rotated cause the advance or retraction of the 45 bolts.

The outer flange 22 of the bushing-ring is designed to coöperate with a flange 27 extending forwardly from the front-face of the first-stage runner 8, said flange being formed 50 at the periphery of said runner where the passages of the runner communicate with the water-ways of the pump-casing. Said flange 27 has formed on its outer surface a groove 28 and when the parts are in the position shown 55 in Fig. 1 said groove is opposite an enlargement 29 formed at the edge of the flange 22, there being a sufficient space between said enlargement and groove to permit communication between the outlet of the runner and 60 the counterbalancing-chamber 19. However, when the bushing-ring 21 is shifted toward the suction-end of the pump, the enlargement 29 will be moved to register with the enlarged edge-portion 30 of the runner- 65 flange 27 and the parts 29 and 30 will be in

such close proximity that the communication just mentioned will be substantially cut off.

The flange 23, which controls the communication between the suction-inlet of the 70 pump-casing and the suction-inlet of the first runner, is slideable over the adjacent edges of said parts from a position in which the space between the runner and suction-inlet is completely closed by said flange, to a 75 position in which it is open, in order to permit the chamber 19 to communicate with the suction-inlet and thereby have the pressure in said chamber substantially the same as that in the suction-inlet. The web 24 connects the flanges 22, 23 in such a manner that when the flange 22 permits communication between the counterbalancing-chamber and the outlet of the first runner, the flange 23 80 will cut off communication between said 85 chamber and the suction-inlet, and vice versa.

For a pump with a horizontal shaft, as shown in Fig. 5, the chambers 14 and 17 at the rear of the runners of the second, third, and following stages are made of such capacity that theoretically the pressure in the same will be exactly equal to that in the chambers 18 and within the suction-inlets of the runners, so that the runners will be exactly balanced and have no end-thrust exerted thereon. In practice, however, there are influences to be considered which prevent this balancing of pressures and the complete elimination of the end-thrust. For instance, when the bulk of water inclosed in 100 the chamber 18 in advance of the runner is considerably greater than that in the opposite chamber 17 at the rear of the runner, it follows that the water in the forward chamber rotates more slowly than in the rear 105 chamber, and hence the hydraulic pressure in the forward chamber is greater than in the rear chamber. Also, when there is a very little more clearance between the coöperating flanges 15, 16 than at the forward edges 110 of the suction-inlets of the runners, the pressure in the chambers 17 will be less than in the chambers 18. In both of these cases there would, therefore, be experienced a certain end-thrust toward the discharge-end of 115 the pump. Even when the pump-runners are balanced by the systems at present in use, it is practically impossible to maintain this balance by reason of the unequal wear of the various flanges. These defects are 120 obviated by the improved adjustable bushing-ring, by means of which the pressure in the counterbalancing-chamber 19 of the first stage may be made to offset or compensate for the difference in pressure between the 125 chambers 14 and 17 and the chambers 18.

Supposing the parts to be in the position shown in Fig. 1, and the communication which exists between the outlet of the first runner and the counterbalancing-chamber 13^x

19 to be so great that an end-thrust is exerted toward the discharge-end of the pump, the bushing-ring 21 is shifted toward the suction-end of the pump by means of its nut and bolt connections. In this manner the enlargement 29 of the flange 22 will be brought into close contact with the enlargement at the forward edge of the flange 27 and the communication will be more or less shut off, 5 so that the pressure in the counterbalancing-chamber will be reduced. In case this decrease in the pressure in the counterbalancing-chamber is insufficient to overcome the end-thrust, the bushing-ring 21 has to be 10 further shifted toward the suction-end of the pump, and a continued movement in this direction will result in the space between the suction-inlet and the inlet of the first runner being uncovered, whereby communication is 15 afforded between the suction-pressure and the counterbalancing-chamber. Inasmuch as the pressure at the suction-inlet is very much less than at the outlet of the runner, the pressure in the counterbalancing-chamber 20 will be very much reduced, so that the end-thrust will be overcome. When the pressure in the chamber 19 becomes too low the bushing-ring must be shifted in the opposite direction, as will be understood. The 25 arrangement of the bushing-ring is especially advantageous as both of its flanges may be moved at the same time in such a manner as to quickly produce the required change in pressure in the counterbalancing-chamber. 30

In the modification shown in Fig. 7, the flanges 31, 32, which control communication between the counterbalancing-chamber and the discharge and suction pressures, instead 40 of being connected, are made separate and independently adjustable. These flanges, however, act in the manner before described. They are adjusted by bolts 31^x and 32^x and nuts 31^y and 32^y. 45

In Fig. 8 there is shown an adjustable bushing-ring 33 which only controls communication between pressure-chamber 37 and chamber 18 in advance of the first runner. This ring is particularly adapted 50 for use with the pressure received from the second or third or any other stage in a multi-stage centrifugal pump. By the adjustment of this ring the pressure in the chambers 18 may be readily controlled. 55

The second part of this invention relates to an improved arrangement of the diffusing-passages or water-ways by means of which the fluid is conducted from the outlet of one runner to the inlet of the runner in the next 60 stage. The object of the improved arrangement of the diffusing-passages is to produce the transformation of the kinetic energy of the fluid leaving the outlet of each runner into potential energy or hydraulic pressure 65 by means of steady changes of velocity.

whereby the efficiency of the pump is increased. When water is discharged through a passage which steadily increases in area so as to avoid shock or impact, its speed will be slowed down at the same rate at which the 70 area of the passage is enlarged. Under these conditions it may be expected that the difference between the original and final kinetic energy is not lost. In practice, nearly the whole amount of this energy is transformed 75 into potential energy, that is to say, the hydraulic pressure is augmented, subject, of course, to the loss of work which must occur by friction of the fluid along the walls of the passages. This principle of hydraulics has 80 been applied in the arrangement of the improved diffusing-passages or water-ways. As shown in Figs. 1 and 5, the water-ways 34 extend from the peripheral portion of each casing-section 5, 6 to the inlet-mouth of the 85 runner of the next stage. At the point where these water-ways communicate with the outlets of the runners they extend transversely of the casing and tangentially to the circumference of the runners, as shown in 90 Fig. 2. Said water-ways increase in cross-sectional area as they extend in outward direction, as shown in Fig. 2, and are curved toward radial direction. When they reach the outer portions of the casing-sections they 95 extend longitudinally of the pump-casing, as indicated at 35. These passages then extend radially toward the shaft, as shown in Fig. 3, the passages being at this point of greater cross-sectional area than at their outer bends, 100 where they extend longitudinally of the pump-casing, and defined by radial ribs 36.

The water or other fluid after leaving the passages of each runner is directed into the tangential portions of the water-ways 34, 105 after which it flows axially of the pump through the enlarged bends 35, after which it is forced back again toward the shaft through the comparatively wide radial portions of said water-ways. In this manner, 110 when the water is discharged tangentially into the diffusing-passages, it has great kinetic energy, but, owing to the gradual increase in cross-sectional area of the water-ways and to the fact that the bends in said water-ways 115 are gradual and not abrupt, this kinetic energy is transformed into potential energy, that is to say, the pressure within the pump is augmented, and hence when the water is delivered to the runner of the next stage said 120 runner receives it at a greatly increased pressure.

As shown in Fig. 3, the axial portions of the diffusing-passages are of semicircular cross-section, this section being favorable for the stream of the fluid as well as for the core of the casting; but any other suitable section may be used. When the water passes radially in inward direction, it passes between the radial ribs 36, the inner ends of which 130

are in close proximity to the inlet-mouth of the adjacent runner.

Having thus described my invention, I claim as new and desire to secure by Letters 5 Patent:

1. In a centrifugal pump, the combination, with a casing and a runner rotatable therein, of a chamber in advance of said runner and communicating with the inlet and outlet of 10 said runner, and means within said chamber to control such communication.

2. In a centrifugal pump, the combination, with a casing and a runner rotatable therein, of a chamber in advance of said runner and 15 communicating directly with the inlet and outlet of said runner, and means within said chamber to control such communication.

3. In a centrifugal pump, the combination, with a casing and a runner rotatable therein, 20 of an annular chamber in advance of said runner and communicating with the inlet and outlet thereof, and means to control such communication from the exterior of the casing.

25 4. In a centrifugal pump, the combination, with a casing and a runner rotatable therein, of an annular chamber in advance of said runner adjacent the peripheral portion thereof and in direct communication by annular 30 spaces with the inlet and outlet of said runner, and means to control such communication.

5. In a centrifugal pump, the combination, of a casing having water-ways, a runner rotatable in said casing and communicating at 35 its peripheral portion with said water-ways, said runner having a suction-inlet, counterbalancing-chambers at the rear of said runner, an annular chamber in advance of said 40 runner and communicating with the inlet and outlet thereof, and adjustable means to control such communication.

6. In a centrifugal pump, the combination of a casing having water-ways, a runner rotatable in said casing and communicating at 45 its peripheral portion with said water-ways, said runner having a suction-inlet, counterbalancing-chambers at the rear of said runner, an annular chamber in advance of said 50 runner and communicating with the inlet and outlet thereof, and an adjustable bushing-ring to control such communication.

7. In a centrifugal pump, the combination of a casing having water-ways, a runner rotatable in said casing and communicating at 55 its peripheral portion with said water-ways, said runner having a suction-inlet, counterbalancing-chambers at the rear of said runner, an annular chamber in advance of said 60 runner and communicating with the inlet and outlet thereof, a bushing-ring to control such communication, and means whereby said ring may be adjusted from the exterior of the pump-casing.

65 8. In a centrifugal pump, the combination,

with a casing, a shaft journaled therein, and runners mounted on said shaft and rotatable in said casing, of counterbalancing-chambers arranged at the rear of said runners, a counterbalancing-chamber in advance of the runner of the first stage, said chamber communicating with the suction-inlet and the outlet of said first runner, means to control the communication between said chamber and said inlet, and means to control communication 75 between said chamber and said outlet.

9. In a centrifugal pump, the combination, with a casing having an inlet, of a runner rotatable in said casing and having an inlet adjacent and in communication with said 80 first-named inlet, a counterbalancing-chamber in advance of said runner and in communication with said inlets, and a flange in said chamber slidable over the adjacent edges of said inlets.

10. In a centrifugal pump, the combination, with a casing having water-ways, of a runner in said casing having its outlet in communication with said water-ways, a counterbalancing-chamber in advance of said 90 runner and in communication with the outlet of said runner, and a flange in said chamber slidable into the space between the periphery of said runner and the adjacent wall of the casing and operable to cut off communication 95 between said chamber and said outlet.

11. In a centrifugal pump, the combination, with a casing, a shaft journaled therein, and runners mounted on said shaft and rotatable in said casing, of counterbalancing- 100 chambers arranged at the rear of said runners, a counterbalancing-chamber in advance of the runner of the first stage, said chamber communicating with the suction-inlet and the outlet of said first runner, a flange to control 105 the communication between said chamber and said inlet, and a flange to control communication between said chamber and said outlet.

12. In a centrifugal pump, the combination, with a casing, a shaft journaled therein, and runners mounted on said shaft and rotatable in said casing, of counterbalancing-chambers arranged at the rear of said runners, a counterbalancing-chamber in advance 115 of the runner of the first stage, said chamber communicating with the suction-inlet and the outlet of said first runner, means to control the communication between said chamber and said inlet, means to control communication between said chamber and said outlet, and means whereby both of said means may be simultaneously adjusted.

13. In a centrifugal pump, the combination, with a casing, a shaft journaled therein, 125 and runners mounted on said shaft and rotatable in said casing, of counterbalancing-chambers arranged at the rear of said runners, a counterbalancing-chamber in advance of the runner of the first stage, said chamber 130

- communicating with the suction-inlet and and the outlet of said first runner, a flange to control the communication between said chamber and said inlet, a flange to control 5 communication between said chamber and said outlet, a web connecting said flanges, and adjusting-bolts for said web.
14. In a centrifugal pump, the combination, with a casing and a runner rotatable 10 therein, of a counterbalancing-chamber in advance of said runner and communicating directly with the inlet and outlet of said runner, and means whereby communication between said chamber and said inlet is opened 15 when communication between the former and said outlet is cut off.
15. In a centrifugal pump, the combination, with a casing and a runner rotatable therein, of a counterbalancing-chamber in 20 advance of said runner and communicating directly with the inlet and outlet of said runner, and means whereby communication between said counterbalancing-chamber and said outlet is cut off and communication with 25 said inlet simultaneously established.
16. In a centrifugal multistage pump, the combination, with the casing having the water-ways and the runners rotatable in said casing and communicating at their outlets 30 with said water-ways, of an annular chamber arranged in advance of the first runner, and an adjustable bushing-ring in said chamber which establishes communication between said chamber and the outlet of the first runner and simultaneously cuts off communication 35 between said chamber and the inlet of said runner, and vice versa.
17. In a multistage centrifugal pump, the combination of a casing, a plurality of runners rotatable therein, a counterbalancing-chamber arranged in advance of the first runner, a bushing-ring in said chamber having a flange to control communication between said chamber and the outlet of said 40 first runner and a second flange to control

communication between said chamber and the suction-inlet, and means whereby said ring may be adjusted from the exterior of the pump-casing.

18. In a centrifugal pump, the combination of a casing having water-ways, a runner rotatable in said casing and communicating at its peripheral portion with said water-ways, said runner having a suction-inlet, a counterbalancing chamber at the rear of said runner, an annular chamber in advance of 55 said runner and communicating with the inlet and outlet thereof, and means to control such communication.

19. In a centrifugal pump, the combination, with a casing, a shaft journaled therein, and a runner mounted on said shaft and rotatable in said casing, of a counterbalancing chamber arranged at the rear of said runner, a counterbalancing chamber in advance of 65 said runner, said chamber communicating with the suction-inlet and the outlet of said runner, means to control the communication between said chamber and said inlet, and means to control communication between 70 said chamber and said outlet.

20. In a centrifugal pump, the combination, with a casing, a shaft journaled therein, and a runner mounted on said shaft and rotatable in said casing, of a counterbalancing 75 chamber arranged at the rear of said runner, a counterbalancing chamber in advance of said runner, said chamber communicating with the suction-inlet and the outlet of said runner, a flange to control the communication 80 between said chamber and said inlet, and a flange to control communication between said chamber and said outlet.

In testimony, that I claim the foregoing as my invention, I have signed my name in 85 presence of two subscribing witnesses.

OSCAR GOERIZ.
